(57) **CLAIM**

The ornamental design for an electrical contactor, as shown and described.

DESCRIPTION

FIG. 1 is a perspective view of an electrical contactor showing my new design;

FIG. 2 is a front view thereof;

FIG. 3 is a first side view thereof;

FIG. 4 is a second side view thereof, wherein the portion of the article shown in broken lines forms no part of the claimed design;

FIG. 5 is a bottom view thereof; and,

FIG. 6 is a top view thereof.
